WAGON BRAKE.

No. 405,062.

Patented June 11, 1889.

UNITED STATES PATENT OFFICE.

LESLIE WETHERBEE, OF CLAYTON, MICHIGAN.

WAGON-BRAKE.

SPECIFICATION forming part of Letters Patent No. 405,062, dated June 11, 1889.

Application filed January 26, 1889. Serial No. 297,698. (No model.)

To all whom it may concern:

Be it known that I, LESLIE WETHERBEE, of Clayton, in the county of Lenawee and State of Michigan, have invented a new and Improved Wagon-Brake, of which the following is a full, clear, and exact description.

The object of the invention is to provide a new and improved brake specially intended for front wheels of wagons and automatically operated from the neck-yoke.

The invention consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a plan view of the improvement with parts in section. Fig. 2 is a side elevation of the same with parts broken out and parts in section, and Fig. 3 is a sectional side elevation of part of the improvement on the line *xx* of Fig. 1. Fig. 4 is an enlarged sectional end elevation of the brake-block.

The wagon A is provided with the front wheels B, mounted to rotate on the axle C, supporting the hounds D, of any approved construction. To the rear end of the hounds are secured rearwardly-extending brackets E, to the under side of which are pivoted links F F, also pivotally connected at their lower ends with longitudinally-extending plates F', fastened by means of clips F² to the brake-beam G, extending transversely in the rear of the front wheels B B. The links F permit a forward and backward swinging of the brake-beam G.

The brackets E are preferably bolted to the hounds D, and are provided with additional bolt-apertures E', to shift the brackets forward or backward to bring the brake-blocks in proper position in regard to the wheels.

Near each outer end of the brake-beam G are secured by clips or other means the bearings H, in which are mounted to turn shafts H' and H², located one above the other, and carrying at their outer ends arms H³ and H⁴, extending toward the front wheels B, and carrying a brake-block I for each wheel B. The lower shafts H² are somewhat longer than the upper shafts H', and on each is coiled a spring H⁵, fastened by one end to the shaft and by

its other end to one of the bearings H. The springs H⁵ serve to hold the brake-blocks I out of contact with the front wheels B when the wagon is backed up and it is not desired to apply the brakes.

Each of the brake-blocks I is provided with two side plates I' and I², of which the latter is provided with a block I³, extending to the inside of the other plate I'. A brake-shoe I⁴ is held in place between the two plates I' and I² by a bolt I⁵, held on the plate I' and passing through the block I³ and side plate I². A nut I⁶ screws on the outer end of the bolt I⁵ against the plate I², and serves to clamp the side plates I' and I² tightly onto the brake-shoe I⁴, so as to hold the latter in place. The brake-shoe I⁴ abuts at its inner end against the front end of the block I³, and can be easily removed and replaced by loosening the nut I⁶ of the bolt I⁵.

On each outer bearing H is secured an arm H⁶, having an outwardly-extending lug H⁷, passing over the uppermost arm H⁸ of the shaft H'. The lug H⁷ serves to prevent the arm H⁸ from swinging too far upward.

To the brake-beam G are pivotally secured the branch arms J' of the rod J, extending forward under the hounds D and provided near its front end with a hook J², into which hooks a chain J³, passing over a pulley J⁴, secured on a shaft J⁵, mounted to rotate in suitable bearings J⁶, secured to the pole K of the usual length and mounted to slide in suitable bearings on the hounds D. The bearings J⁶ project downward, so that the shaft J⁵ is below the pole K. On the shaft J⁵ is also secured a larger pulley J⁷, over which passes a chain J⁸, secured by one end to the periphery of the said pulley, and then extending forward onto the pole K, to pass over a pulley J⁹, mounted to rotate in suitable bearings in the front end of the pole K. The outer end of the chain J⁸ is passed rearward and upward and connected with the neck-yoke L, held in any suitable manner on the front end of the pole K.

The rod J, before mentioned, is pivotally connected near its front end with a lever N, fulcrumed at N' on a rear bearing N² of the pole K, said bearing N² being secured to the hounds and the fifth-wheel, as is plainly shown in Figs. 1 and 2.

The upper end of the lever N is pivotally

connected by a link O with a bar P, mounted to slide in suitable bearings K' on the top of the pole K. On the bar P is formed a U-shaped keeper P', through which passes the doubletree Q, to which the horses are hitched, said doubletree Q being pivoted on the bolt P² passing through the keeper P' and through a slot K² extending longitudinally in the pole K. The bolt P² slides forward and backward 10 with the keeper P'; but this movement is limited by the length of the slot K², through which the said bolt passes.

The operation is as follows: As illustrated in Figs. 1 and 2, the brake is off, and is held 15 in this position by the action of the springs H⁵. The horses pulling the wagon A are hitched to the doubletree Q and the neck-yoke L in the usual manner, and when the wagon passes down an incline the horses pull the 20 neck-yoke rearward, so that the chain J⁸ rotates the pulley J⁷ in the direction of the arrow a', whereby the chain J³ is wound upon the pulley J⁴ on the same shaft J⁵ as the pulley J⁷. The winding up of the chain J³ causes 25 a forward motion of the rod J, so that the brake-beam G is moved in the same direction, swinging on the links F, supported from the hounds. The swinging motion of the brake-beam G throws the brake-blocks I, with the 30 brake-shoes I', in contact with the front wheels B, whereby the wheels are braked. The forward motion of the rod J causes a swinging of the lever N, so that the link O is pulled rearward, and thereby moves the rod P and the doubletree Q in the same direction until 35 the bolt P² rests against the rear end of the slot K² in the pole K. When the wagon has passed onto level ground, the horses commence to pull on the doubletree Q, so that the keeper 40 P', with the rod P, is moved forward, thereby exerting a forward pull on the link O, which causes the lever N to swing, whereby the rod J is moved rearward. This motion causes a rearward swinging motion of the brake-beam 45 G, so that the brake-blocks I are thrown out of contact with the front wheels B. When the wagon is backed up, the horses exert a pull against the neck-yoke L in the same manner as above-described, so that the brake-blocks I are thrown toward the front wheels 50 B; but as the latter turn in the opposite direction the brake-blocks are held out of contact by the action of the springs H⁵. Thus it will be seen that the wagon is automatically 55 braked from the neck-yoke when it passes down an incline, and the brake is thrown off automatically the moment the horses begin to pull on the doubletree.

The brake, as shown, is attached to platform-wagons, but may equally well be adapted for other styles of wagons, such as lumber-wagons, &c.

Having thus described my invention, what I claim as new, and desire to secure by Letters Patent, is—

1. In a wagon-brake, the combination, with

the pole and the neck-yoke held thereon, of a brake-beam connected with the said neck-yoke and mounted to swing, arms held to turn on the said brake-beam, and brake-blocks pivotally connected with the said arms, substantially as shown and described. 70

2. In a wagon-brake, the combination of a brake-beam suspended from the rear ends of the hounds by means of a pivotal connection, 75 and brake-blocks pivotally connected to the beam, substantially as described.

3. In a wagon-brake, the combination, with a brake-beam mounted to swing, of a set of parallel arms mounted to turn on each end of the said brake-beam, and a brake-block pivotally connected with the outer ends of each set of the said parallel arms, substantially as shown and described. 80

4. In a wagon-brake, the combination, with 85 a brake-beam mounted to swing, of a set of parallel arms mounted to turn on each end of the said brake-beam, a brake-block pivotally connected with the outer ends of each set of the said parallel arms, and a spring held on 90 each set of parallel arms to hold the said brake-blocks out of contact with the wheels when backing up the wagon, substantially as shown and described.

5. In a wagon-brake, the combination, with 95 a brake-beam mounted to swing, of a set of parallel arms mounted to turn on each end of the said brake-beam, a brake-block pivotally connected with the outer ends of each set of the said parallel arms, and a lug secured on 100 each end of the brake-beam and passing over one of the said parallel arms to prevent the brake-blocks from opening too far, substantially as shown and described.

6. In a wagon-brake, the combination, with 105 the pole and the neck-yoke held thereon, of a pulley held in the front end of the said pole, a chain passing over the said pulley and connected with the neck-yoke, a shaft held near the rear end of the said pole and carrying a 110 large pulley, on which winds the said chain, a second smaller pulley held on the said shaft, and a second chain held on the said pulley and connected by a rod with a swinging brake-beam, substantially as shown and described. 115

7. In a wagon-brake, the combination, with the pole and the neck-yoke held thereon, of a pulley held in the front end of the said pole, a chain passing over the said pulley and connected with the neck-yoke, a shaft held near 120 the rear end of the said pole and carrying a large pulley on which winds the said chain, a second smaller pulley held on the said shaft, a second chain held on the said pulley, a rod connected with the said second chain, and a 125 brake-beam mounted to swing and connected with the said rod, substantially as shown and described.
